DESIGN FOR AN ELECTRIC CLOCK

Joseph Gottlieb, Deal, N. J.

Application April 29, 1941, Serial No. 100,697

Term of patent 7 years

To all whom it may concern:

Be it known that I, Joseph Gottlieb, a citizen of the United States and a resident of the city of Deal, county of Monmouth, and State of New Jersey, have invented a new, original, and ornamental Design for an Electric Clock, of which the following is a specification, reference being had to the accompanying drawing forming part thereof.

Fig. 1 is a front elevational view of an electric clock showing my new design, and

Fig. 2 is a top plan view of the same.

I claim:

The ornamental design for an electric clock, as shown.

JOSEPH GOTTLIEB.
